ATTORNEY.

UNITED STATES PATENT OFFICE.

CHARLES S. CHRISMAN, OF WEST CHESTER, PENNSYLVANIA.

CHAMBER-HEAD.

1,374,490.

Specification of Letters Patent. Patented Apr. 12, 1921.

Application filed May 1, 1917. Serial No. 165,720.

To all whom it may concern:

Be it known that I, CHARLES S. CHRISMAN, a citizen of the United States, and a resident of West Chester, in the county of Chester 5 and State of Pennsylvania, have invented a certain new and useful Chamber-Head, of which the following is a specification.

The principal object of the present invention is to provide an internally conical head 10 for chambers consisting throughout of bricks of the same shape, and not necessarily of more than two sizes, and which can be laid in self-supporting courses without the use of false work.

15 The invention will be claimed at the end hereof but will be first described in connection with the embodiment of it chosen for illustration in the accompanying drawing forming part hereof and in which—

20 Figure 1, is a transverse sectional view of a conical head embodying features of the invention, and

Fig. 2, is a perspective view, drawn to an enlarged scale, of one of the bricks.

25 Each brick 8, is generally wedge-shape in plan, *i. e.* the end *b*, is narrower than the end *a*, and each brick is conical in end elevation, *i. e.* the top edges of the ends *a* and *b* (Fig. 2) are narrower than the bottom edges, and 30 the bricks are offset at 9, *i. e.* one end portion is offset in respect to the other end portion. For the sake of further description it may be said that each brick is tapered in two directions in planes at right angles to or nor-

35 mal with each other, and has the shape of a solid part or segment of the conical wall, the axis of the part being inclined to the axis of the cone when the brick is in place. It may be remarked that these bricks have their end 40 faces, *a* and *b*, at right angles to the major axes of the bricks, and thus no fragile knife edges are presented. The entire head can be constructed by an appropriate combination of bricks of two sizes, one corresponding to 45 the course at the base of the cone and the other corresponding to the course near the

apex of the cone, and descriptively it may be said that the intermediate courses contain bricks of each size. It is an advantage that by making the base line, *i. e.* the lower edge 5 of *b*, Fig. 2, equal to the constant represented by the Greek letter Pi, the bricks can be laid in circular courses of different diameters within wide limits. Ordinarily the base line may be 3.1416 inches and the diameters may 55 range from about 7 to 12 feet. Those skilled in the art will know that half bricks may be used if and where desired.

The first course of the described bricks is shown as laid upon a bed *c*, Fig. 2, and in 60 laying this course the offset 9, serves to lock each brick in place during the operation and this is true of each additional course so that no false work is required for the entire structure is self-supporting. This can be done 65 from the inside of the shell 3, with the head 2, attached thereto.

The internally conical head 1, of the described bricks, is shown as constituting the refractory lining of the conical head 2, of 70 the shell of a gas generator 3, having an off-take 10, an inlet 11, and a working floor 13, with space at 12, beneath the floor, but there is no novelty in the shape of the head 2, of the shell, and this invention is capable of 75 many additional uses.

What I claim is:

An internally conical head for a chamber comprising bricks of which the two opposite sides taper in the direction of the length of 80 the brick and in the direction of the thickness of the brick and of which the top and bottom and the two ends are parallel respectively and said bricks having one of their end portions offset in respect to the other of 85 their end portions, substantially as described.

CHARLES S. CHRISMAN.
